(Continued)

Primary Examiner — George D. Kirschbaum*Assistant Examiner* — Joseph J Kukella(74) *Attorney, Agent, or Firm* — Thompson Hine LLP(57) **CLAIM**

The ornamental design for tire tread, as shown and described.

DESCRIPTION

FIG. 1 is a perspective view of the design;

FIG. 2 is a front view of the design of FIG. 1;

FIG. 3 is a side view of a first side of the design of FIG. 1;

FIG. 4 is a side view of a second side of the design of FIG. 1; and,

FIG. 5 is a detail view of a portion of FIG. 1.

The dash-dot-dash lines show the boundary of the claimed design and form no part of the claimed design.

1 Claim, 5 Drawing Sheets(56)
